COMBINED COMPUTER CONTROL PANEL AND PRINTER

Bradley A. Beals, Bloomington, Raymond J. Gormley,
Prior Lake, and Jay Sucre, Newport, Minn., assignors
to Sperry Rand Corporation, New York, N.Y., a cor-
poration of Delaware

Filed Apr. 26, 1961, Ser. No. 64,906

Term of patent 14 years

(Cl. D26—5)

FIGURE 1 is a perspective view of a combined computer control panel and printer showing our new design;

FIGURE 2 is a side elevational view thereof;

FIGURE 3 is a top plan view on a slightly reduced scale;

FIGURE 4 is a back view on the scale of FIG. 3; and

FIGURE 5 is a perspective view of the FIGURE 1 apparatus without the dotted illustration of a keyboard.

The essential features reside in the portions shown in the full lines.

We claim:

The ornamental design for a combined computer control panel and printer, substantially as shown and described.
